*Fig. 8**Fig. 9**Fig. 10*FIG. 1 is a perspective view of a lavatory fitting unit showing my new design;

FIG. 2 is a top plan view of the same;

FIG. 3 is a front elevational view thereof;

FIG. 4 is a rear elevational view of the fitting;

FIG. 5 is a side elevational view of the lavatory fitting unit;

FIG. 6 is a perspective view of a modified form of the lavatory fitting shown in FIG. 1;

FIG. 7 is a top plan view of FIG. 6;

FIG. 8 is a front elevational view of said modified form;

FIG. 9 is a rear elevational view of FIG. 6; and

FIG. 10 is a side elevational view of said modified form.

The dominant features of the design reside in the portions shown in full lines.

The present application is a continuation of my prior co-pending design applications Serial No. D. 54,109, filed January 9, 1959, and Serial No. D. 54,115, filed January 9, 1959.

I claim:

The ornamental design for a lavatory fitting unit or similar article, as shown and described.
